ENVELOPING MACHINE

Matthew Vierengel, Brooklyn, N. Y., assignor to
 M. Vierengel Machine Co. Inc., Brooklyn, N. Y.,
 a corporation of New York

Application July 10, 1931, Serial No. 549,813

37 Claims. (Cl. 93—3)

This invention concerns an enveloping machine, more particularly a machine for covering a flat object by building up an envelope around the said object.

5 One of the objects of this invention is to cover, in rapid succession, a plurality of similar flat objects, boards, booklets, magazines, catalogues, etc., hereinafter referred to as books, by an envelope extending over the front and back and 10 all sides, and either completely sealed, or partly sealed, the enveloped object being in the latter case openable without unsealing as required for certain classes of mail.

Another object of my invention is to provide 15 a mechanism in which the flat objects to be enveloped are placed onto an envelope blank, said envelope then being closed over the object.

A further object of this invention is to provide 20 a continuously moving carrier for envelope blanks, to place flat objects onto said blanks on said carrier, and to close said blanks so as to envelop them.

Another object of this invention is to use for 25 such a carrier a continuously rotating drum which is spacedly flattened off in order to offer enveloping position.

A further object of my invention is to provide 30 a machine which is adapted to enclose flat objects into envelopes in a continuous, rapid procedure, so that machinery which prepares the blanks from a roll of paper, may be connected to my machines at one end thereof and so that machinery for printing, addressing and providing the closed envelope with postage, or otherwise conditioning the envelope for mailing, may be added on said machine on the other end thereof.

A further object of this invention is to provide 35 in connection with a machine continuously enveloping flat objects, machinery cutting blanks for the enveloping process at a synchronous operating speed.

Other objects of my invention will be brought forth from the following description:—

40 My machine provides a carrier for envelope blanks, means positioning envelope blanks on such carrier and positioning the book to be enveloped on top of said blank, and means tightly closing and sealing said blanks around the books 45 so that they are fully enveloped, and are delivered from said carrier in envelopes. The carrier may be a conveyor, but preferably it is a continuously rotating drum or table, on which are provided a plurality of flat positions fitting the 50 books. At those positions, while being operated

upon by relatively stationary devices which however move therewith on said drum or said table, the blanks are folded in, closed and sealed over the books.

The enveloped objects are of course in an up-side-down position, when leaving said carrier; the machine also comprises means for reversing the enveloped objects, so that they rest upon their backs, for the purpose of printing or stenciling the face of the envelope. The drawings illustrate some particular modifications by means of which I execute my invention.

In the drawings:—

Fig. 1 shows, in a top view, the general assembly of a machine of my invention. The part of the machine at the bottom of this drawing will hereafter be referred to as a front thereof, the part at the upper end of the sheet will be called the rear of the machine; the left side of the machine will be called the hand wheel side or wheel side of the machine, because it is the side from which the machine is ordinarily approached for the purpose of adjustments and for turning it over by means of the hand wheel shown on that side. The part of the machine facing towards the right of Fig. 1 will be referred to as the gear side of this machine.

Figs. 2, 3, and 4 show connecting views of the hand wheel side of my invention. Fig. 2 shows the cutting and feeding mechanism at the rear 30 of the machine. Fig. 3 shows the center drum part of the machine, the book feed which protrudes from the hand wheel side of the machine as shown in Fig. 1, being omitted. Fig. 4 shows the front,—delivery,—end of the machine, comprising exemplary means for printing or marking 35 the face of the envelope.

Fig. 5 shows the developed circumference of the female blanking cylinder. The envelope blank together with the waste parts cut therefrom on said cylinder are super-imposed upon this view; and it also shows in a dashed-line a smaller envelope in correct position in relation to the stationary part of the cylinder, towards which the other parts may be adjusted.

Fig. 6 shows the blanking cylinders in a detail view taken from the hand wheel side of the machine.

Fig. 7 shows, in a similar side view, part of the cut-off cylinders, by means of which the envelope blanks are cut into the correct length from a paper roll.

Fig. 8 shows a sectional view of the cut-off knife.

Fig. 9 shows a front view of the book feeding 55

mechanism, which protrudes from the hand wheel side of my invention.

Fig. 10 shows one set of the plates, which support the blanks on the drum. The front flap plate 5 is developed into the plane of the book supporting plate. The view also comprises the side folders and developed parts of the respective operating cams, and of the drum flanges. An envelope blank is super-imposed in dot-dashed lines.

10 Fig. 11 shows in a sectional sectioned front view the blank gripper mechanism on the hand wheel side of the machine. In this and in later views, that mechanism is arranged on the wheel side of the wheel side drum flange whereas in 15 Fig. 3, it was shown to be exemplarily arranged on the other side thereof.

Fig. 12 shows, in a sectional sectioned front view, projected over from Fig. 10, the side folders and their operating means.

20 Fig. 13 shows a wheel side view, illustrating the rear and front folders in various operating positions, superimposed upon the gear side part of the frame, in which:—

Sector A of Fig. 13 more particularly shows, 25 in a sectional sectioned view, a rear folder before folding.

Sector B of Fig. 13 shows, also in a sectioned view—but supported by a full web of the gear side drum flange—the same, after folding.

30 Sector C of Fig. 13 shows the front folding mechanism and the closing roller in a side view in which just the wheel side drum stand is removed.

The directions in which these two last views 35 are taken are indicated by arrows and indices 13B and 13C, respectively, in Fig. 14.

Sector D of Fig. 13 shows the front folder mechanism in closed position.

Fig. 14 shows a top view related to sector B of 40 the view of Fig. 13.

Fig. 15 is a sectioned detail view of the adjusting means for the cut-off and blanking cylinders.

Fig. 16 is a sectioned parallel perspective,—seen 45 from the wheel side,—of the book feed.

Fig. 17 illustrates by a similar view, how the transverse book feed may be dispensed with.

Fig. 18 shows a wheel side view, in which the wheel side drum stand has been removed. It 50 includes a preferred modification of the front folder and of the respective operating mechanism, a back folder, a gripper, and the delivery carriage.

Fig. 19 shows a corresponding front view. (The gripper parts are omitted.)

Fig. 20 shows a detail top view of the delivery 55 carriage.

Fig. 21 shows a large envelope blank.

Fig. 22 shows the supporting plates adjusted for such a blank.

Fig. 23 shows a small envelope blank.

60 Fig. 24 shows the supporting plates adjusted for such a blank.

Fig. 25 shows the blank of Fig. 23 closed over a book. The flaps of the blank are termed in accordance with the sides of the machine towards 65 which they extend while the blank travels over the top of the drum.

The frame generally comprises pairs of similar stands and brackets, which, respectively are arranged upon the side of the hand wheel 31 and 70 of the gears 32. From the hand wheel side 33 of the frame sideways extends the feed conveyor 35 for the books. The drive of the machine is arranged upon the gear side 34 of the frame, where I provide the tight and loose pulleys 36 on the 75 main shaft 39. The shaft 39 is journalled in the

wheel side drum stand 37 and gear side drum stand 38 of the frame, which arise from the floor stands 41 and 42, respectively. The main shaft 39 carries the hand wheel 31 at its wheel side end, whereas it carries the gear pinion 40 on the gear side, between the respective drum stand 38 and pulleys 36.

The linear speed, at which a point of the pitch circle of pinion 40 travels around the main shaft 39, determines the speed at which the envelopes 10 and the enveloped objects move through the enveloping machine. The drum 43 is provided with three flat positions 44 upon its circumference. Each one of these positions accommodates an envelope and a book during the operation of the enveloping machine, each one of said envelopes and books being worked upon by a corresponding number of devices which rotate with the drum, and each one of said devices being operated or actuated by a stationary single cam mechanism, 15 as it passes said mechanism. Such mechanisms are mounted upon the sides 33 and 34 of the frame. The positions 44 and the devices respectively associated therewith, are indexed in the drawings by the letters A, B and C, in the rotation 20 in which said positions receive the envelope blanks and books at the feeding end, and carry them through the enveloping process to the front of the machine. The drum 43 comprises a pair of drum flanges 45 and 46 which are fixedly 25 mounted upon the drum shaft 47. The drum shaft 47 is journalled upon the drum stands 37 and 38 and it carries at the gear side end the large gear 48, which meshes with the pinion 40. There being three operating positions upon the drum 43, the drum passes through three operating cycles during one revolution. Cam shafts and cylinders, by means of the mechanism on which I cyclically operate upon the books and envelopes are therefore provided with driven gears of one-third the pitch diameter of the large gear 48 and 30 are connected thereto by a continuous chain of gears. Generally, the ratio of the drum gear to said driven gears equals the number of positions 35 on the drum.

The chain of gears comprises a gear 50, which 40 is mounted upon a shaft 49. The shaft 49 is adjustably journalled upon the brackets 51 and 52 which extend from the circumference of the drum stands 37 and 38 in a direction substantially radial 50 to the drum shaft 47. A pinion 54 meshes into the gear 50 (but not into the gear 48 since it rotates in the same direction). The pinion 54 is mounted upon a shaft 53, which is journalled upon the brackets 55 and 56 (not shown) radially extending from the drum stands 37 and 38. The gear chain continues from gear 50 to gear 56, which rotates the cam shaft 57 through one revolution during one cycle of enveloping operations.

The shaft 57 is supported by a bracket 60 upon the gear side and by a bifurcated bracket 59 upon the wheel side of the machine, one bifurcation of said bracket extending outwardly on the wheel side so as to support the shaft 57 underneath the book conveyor 35.

Near the rear end of the machine the stands 61 and 62 arise from the wheel side and gear side stands 41 and 42 of frames 33 and 34. Between the stands 61 and 62 the paper feeding and cutting mechanism is accommodated. The female 70 and male blanking cylinders 63 and 64 are journalled, suitably adjustably towards each other, upon the shafts 65 and 67. The shafts 65 and 67 are connected to each other and gear 58 by similar gears 66 and 68.

Tierods 69 and 71 connect the stands 61 and 62 above the blanking cylinders. They respectively carry the idler gears 70 and 72, by means of which the gears 74 and 76 on the shafts 73 and 75 of the cut-off cylinders 77 and 78 are synchronously operatively connected to the gears 66 and 68 of the blanking cylinders.

The cyclically synchronized chain of gears, which rearwardly extends from the pinion 40 ends 10 with gears 74 and 76. But gears 82 and 84 of the feeding cylinders 79 and 80 are connected to said chain of gears, by compounded gearing or by change gears 86 and 85. The gears 85 and 86 are detachably connected to each other, for instance 15 by a key sleeve, as commonly known to machinists, and said key sleeve is rotatably mounted upon a suitable shoulder screw 89, which is clamped by a nut 87 upon an ear 88 extending from the stand 62. The ear 88 is provided with a slot 90 which 20 is substantially concentrically disposed to the cut-off cylinder shaft 73. The gear 86 meshes upon the gear 74 and the gear 85 meshes with the gear 82. According to whether a larger or smaller 25 change gear 85 is used,—shoulder screw 89 being correspondingly adjusted more or less rearwardly in slot 90,—the feed cylinders 79 and 80 will be rotated at more or less speed as compared with the synchronized gearing of the enveloping machine.

The shafts 81 and 83 are adjustably journalled upon the stands 61 and 62, so that the cylinders 79 and 80 grippingly clear the blank paper 91. The roll 92 containing the blank paper 91 is mounted with suitable retarding means upon two 35 brackets rearwardly extending from the main stands 41 and 42. The roll 92 is transversely adjusted into suitable alignment with the feeding parts of my machine. Exemplarily I have arranged the showing of my drawings in such a 40 manner, that all adjustments for a difference of width of the blanks and the books are made upon the wheel side of the machine. The roll 92 will therefore be adjusted in this machine, so that it always aligns in the same manner upon the 45 gear side, wider or less wide rolls of paper extending more or less towards the hand wheel side of the machine.

From the roll 92 the paper passes over an idler roller 93 which is suitably mounted upon arms 50 rearwardly extending from the stands 61 and 62. The change gear 85 is chosen, so that the positively feeding cylinders 79 and 80 feed during one cycle of the enveloping machine (one revolution of the cutting and blanking cylinders 77, 78 and 63, 55 64,) the length of paper 91 corresponding to the exact length of the envelope blank to be cut.

From the feeding cylinders 79 and 80 the paper is suitably fed between the cut-off cylinders 77 and 78. Like the blanking cylinders the cut-off 60 cylinders 77 and 78 rotate in opposite directions at the same circumferential speed, one of said cylinders, exemplarily cylinder 77, (Fig. 7) being fully or partly covered with felt or cloth 94 so that the paper is swept in-between the cut-off cylinders by what is called a brush feed. By that term I understand a feeding which is not positive, but which will feed the stock at the speed at which it is delivered from the feeding cylinder 79, provided that the feeding cylinders rotate at the same or at 65 a lower circumferential speed than the cut-off cylinders 77 and 78, the paper slipping between the cylinders 77 and 78 to the extent to which the speed of said cylinders exceeds the speed of the feeding cylinders 79 and 80. The felt 94 clears a 70 transverse groove 95 provided in cylinder 77, a

channel 96 being inserted into the cylinder for that purpose.

Across the cylinder 78 extends a knife 97. Owing to the gearing 74, 86, connecting the cut off cylinders 77 and 78, the groove 95 and the 5 knife 97 register with each other, the knife entering upon the groove once upon each revolution of the two cylinders. The knife 97 is exemplarily shown in Fig. 8 as a serrated knife, the cutting edge 98 being suitably notched. The knife 10 97 is removably mounted in a suitable slot in cylinder 78, and alongside of knife 97 there are recesses 99 in the cylinder, in which are radially slidably mounted the bars 100. These bars are retained in the cylinder by the heads of pins 101, 15 which are radially mounted in recesses 99 and which slidably extend into the bars. The compression springs 102 are disposed upon the pins 101 in the recesses 99 and act between the bottom of the recesses 99 and the bars 100. Normally 20 the bars 100 protrude from the circumference of cylinder 78, substantially shielding the knife 97. But when the knife 97 and the groove 95 come to register with each other during the rotation of the cylinders 77 and 78, the bars 100 press the 25 paper 91 onto the face 103 of the channel 96. The bars, thus tensionally engaging the paper 30 91, are pressed back into the recesses 99; the knife 97 enters upon the slot 95, and cuts the length of the paper blank 104 (Fig. 7) which has 35 been fed through between the cylinders 77 and 78 from the paper which is just about to enter therebetween. At that time the length of paper 104 is just entering between the blanking cylinders 63 and 64.

The transfer of the paper stock from one pair of cylinders to the next pair of cylinders, and the insertion of the paper in-between the latter may be assisted by suitable switches as commonly known in the art of manufacturing articles from 40 sheets; such switches are shown in Fig. 6, in connection with the delivery of the paper from between rollers 63 and 64 to a conveyor tape.

Since preferably the paper is fed at a positive speed between the cylinders 63 and 64, the distance between the cut-off cylinders 77 and 78 and the blanking cylinders 63 and 64 should exceed the length of the longest envelope blank cut by the former, contrary to the showing of Fig. 2 in which the length of the blank 104 50 exceeds that distance. The transfer of the blanks,—after they have been cut off by cylinders 77 and 78,—to the blanking cylinders 63, 64, may then cyclically be brought about by suitable conveyor tapes, endlessly extending in the space 55 between cylinders 77 and 63, and cylinders 78 and 64. Such conveyor bands are commonly known in the art of paper manufacture and are used elsewhere in this machine as will be explained later.

The blanking cylinders 63 and 64 are not shown in detail in Fig. 2. The manner, in which I arrange these cylinders in order to obtain adjustability for different size envelope blanks, is shown in the gear side view of Fig. 6 and in the 65 developed view of the blanking cylinder 63 given in Fig. 5.

The cylinder 63 comprises two wheels 105, one of which is fixedly mounted upon the shaft 65, in predetermined alignment with the gear side of 70 the paper stock fed through the machine; the second wheel 105 is transversely adjustably mounted upon the shaft 65, that wheel being kept in angular alignment with the first wheel by the feather key 107. Between the wheels 105 75

I arrange one or more discs 108 (not shown in Fig. 6), which serve to support the blank intermediary to the wheels 105. Similar wheels (not shown) of cylinder 64 support the endless tapes 5 141 (Fig. 2). The sectors 109 and 110 are the only parts of the wheels 105 proper, which protrude to the cylinder diameter, and which come into contact with the blank passing between the cylinders. The balance of the circumference of 10 the wheels are recesses 111 and 112, the bottoms of which are concentric with shaft 65. In these recesses are circumferentially slidably accommodated the substantially half-round segments 113 and 114. Screws 116 serve to set the segments 15 at any angle around the circumference of the wheels, the cylindrical surfaces of the segments being in circular alignment with the surfaces of the sectors 109 and 110.

Upon the developed surface of the wheels, a 20 large envelope blank 117 is shown to be placed in position, in Fig. 5. From the body of said blank extend the large front flap 118, the rear flap 119 and the wheel side and gear side flaps 120 and 121. The surface of the sectors 109 and 110 and 25 segments 113 and 114 are shown to be provided with substantially transverse grooves 122, 123, 124 and 125, in alignment with the sides of the side flaps 120 and 121 of the blank. From the 30 inner ends of said grooves extend substantially circumferentially the grooves 126 and 127, 128 and 129, up to the ends of the sectors and segments respectively. These grooves confront the rear and front flaps 119 and 118 of the blank, respectively. In the corners of the sectors and 35 the segments which are separated from the blank by the grooves 122—129, short pins 130 protrude from the sectors and segments and engage upon the waste pieces 131, which are cut out of the length of the paper stock 104 by the blanking 40 operation. The sectors and segments may be provided with circularly disposed grooves 132 and 133, which serve to accommodate switches, by means of which the waste 131 is stripped off the cylinder 63, and by means of which the blank 45 is guided over to and around the male cylinder 64, respectively. The grooves 132 may be omitted if scrapers 134, which are provided with clearance spaces for the pins 130 are used for removing the waste. The waste, which is thus 50 removed from the cylinder 63, drops by way of a chute 135 into a waste bin 136 (Fig. 2).

A tongue 137 slidably extends from the segment 113 into a corresponding groove 138 in segment 114. This tongue and groove arrangement serves 55 to keep the segments 113 and 114 in angular alignment during adjustments.

A smaller envelope blank 139 aligns in Fig. 5 with the envelope blank 117 at the corner between the rear flap and the gear side flap. The outline 60 of the part of the smaller blank, which does not align with the large blank 117, is indicated by a dashed line. It is readily seen, that the blanking cylinder may be adjusted to fit the smaller blank 139 by first adjusting the wheel 105 along its 65 feather key-way towards the wheel 106 and by then adjusting the segments 113 and 114 towards the sectors 109 and 110. The grooves 122—129 function substantially in the manner of the grooves 95, registering knives, similar to the knife 70 97 of the cut-off cylinder, being arranged longitudinally and transversely upon the male blanking cylinder 64. The cylinder 63 is, however, not covered with a felt 94, because we have a positive feeding in the blanking operation, whereas there 75 is a brush feed in the cut-off operation. Cylinder

64 may be provided with suitable clearance openings for pins 130. The knives of the blanking cylinder 64 are provided in the drawings (Fig. 6), as far as they are shown, with the same numerals 5 to which numerals in each instance the index A has been added. The parts of the male blanking cylinder, as far as shown, are indicated by the numerals of the corresponding parts of the female blanking cylinder; but to these numerals are 10 also added the indices A.

For the purpose of tensionally gripping the blank paper and the paper blanks between the various pairs of cylinders, I show, in Fig. 15, the journaling means of the respective shafts, or of 15 one of the respective pairs of shafts. This substantially bisected sectioned top view of one of the bearings exemplarily applies to shaft 73. The journal boxes 157 are longitudinally slidable in the stand 61. The set screw 158 is recessed on its 20 end, the pivot 159 supporting a compression spring 161 which at its free end is seated in a hole 160 countersunk into the box 157. The springs 161 provide the pressure for tensioning the cylinders into gripping engagement with the 25 blank paper or paper blanks. But that tension would normally not be sufficient, to perform the cutting and blanking operations in a positive manner. For that reason the screw 158 is flat at its bottom, and is set by means of the nut 162 so 30 that it comes to rest against the bottom of the hole 160, and prevents the cylinders from being pressed further outwardly against the tension of springs 161, when the cutting operation is performed.

A switch 140 serves to guide the blank, as delivered from the blanking cylinders, around cylinder 64 onto the endless tapes 141. These tapes extend around the idler pulley 142 which is rotatably mounted between the stands 61 and 62, 40 the take-up pulley 143, which is adjustably mounted between the stands 41 and 42, and the driving pulley 144, which is mounted upon the shaft 53.

A second switch 145, (Fig. 6) serves to retain 45 the blank upon the endless tape 141, where said tape parts from the cylinder 64; then the blank is tensionally engaged between the endless tapes 141 and the endless tapes 146; the latter extend from an idler pulley 147 mounted upon a rearward extension 148 of brackets 59 and 60 over a pulley 149, mounted on shaft 49. Gears 50 and 53 serve to drive the tapes 141 and 146 at corresponding linear speeds.

The blank is guided upwardly around pulley 55 149, resting upon tape 146, by a switch, (not shown), so that it comes into tangential alignment with the circumference of drum 43; and its arrival upon the drum is timed so that the front end of the blank aligns with the transverse 60 front edge of a cylindrically shaped flat plate 150 extending across drum 43 (Fig. 3).

From the drum shaft 47 extend substantially radially the three arms 151 of spider 152. The plates 150 are circumferentially adjustable upon 65 the drum as will be explained later. The spider 152 may be suitably spaced in relation to the end of plate 150, by being angularly adjusted upon the shaft 47. For that purpose, slotted arms 155 extend from the arms 151 of the spider 152, the slots 70 in arms 155 being concentrically disposed in respect to the drum shaft 47. The screws 156 extend through the slots in arms 155 into the spokes of the drum flanges 43 or 44 so that the spiders, which abut upon the wheel side or upon the gear 75

side, of the wheel side and the gear side flanges, may be adjusted in relation to said flanges. From a transverse, rotatable shaft 153 at the free ends of the arms 151, extend the grippers 154, which engage the blank upon the plate 150, when swung in a counterclockwise direction into position 154A.

The shaft 153 is connected by a chain of gears 163, 164 and 165—rotatably mounted on the hand wheel side spider,—to a transverse shaft 166, which is supported by the spider arms on both sides of the machine, and which carries at its free end, at the hand wheel side, a lever 167 (Fig. 11). Lever 167 carries at its free end a roller 168. That roller is suitably tensioned (not shown) onto a substantially annular cam 169 which is mounted upon the inside of the web of the wheel side drum stand 37. As seen in Fig. 3, the cam 169 is provided with a high part 170 extending around about half the circumference 20 thereof, said high part swinging the gripper 154 into the blank engaging position 154A. A depression 171 in the cam 169 causes the gripper 154 to swing from the blank engaging position 154A through about approximately 180 degrees 25 into a position in which the other end 172 of the gripper is swung out from between the drum flanges through a clearance opening 173 in plate 150 (Fig. 10), thus kicking up the front flap 118 of the envelope from plate 150 so that it may 30 suitably be engaged upon by means folding that flap over onto the book.

Fig. 10 also shows that the curved plate 150 supporting the front flap 118 of the blank comprises a stationary part 174 and a longitudinally adjustable part 175, which is adjustable upon the circumference of the drum flanges 45 and 46, so that the points at which the front flap is gripped, may be longitudinally adjusted in respect to the book supporting plate 176. The 40 latter one is transversely adjustable in width so that it may be set to the exact width of the book supported thereby. The transversely adjustable part 177 engages upon the stationary part 178 in groove fashion, and bars 179 extend between 45 the flanges 145 and 146, for the purpose of adjustably supporting part 177.

The book feed 35 (Figs. 1, 2, 9, 16 and 17) is supported upon two rods 180 and 181 protruding from the hand wheel side of the drum stand 37 and of the stand 61, respectively. The rods 180 and 181 are connected by brackets 182 and 183, which respectively carry the angles 184. The brackets 182 and 183 may be transversely adjusted upon the rods 180 and 181, so that the 55 vertical sides of the angles clear the exact width of the books 185.

The books rest frontwardly against a plate 186 which is supported by the brackets 182 and 183 in a position at right angles to the extent of the 60 angles 184; the plate extends transversely from the book feed into the machine substantially up to the slightly more inclined plate 187, the upper end of which faces the circumference of the drum 43. The plate 186 is transversely slotted 65 where it extends up from the angles 184 substantially to the width of said angles. Through these slots 188 (Fig. 9) extend endless belts 189, the upper extents of which are slidably supported by the angles 184; the looped ends of the belts 70 are supported by idler pulleys 190 on shaft 181 and by driving pulleys 191 on a shaft 192, which is supported by the brackets 182 and 183. The idler pulleys 190 form one unit with the sprocket 193, said unit being rotatably mounted upon 75 the rod 181. Sprocket 193 is connected by chain

194 to sprocket 195 which is mounted upon the shaft 192 and which is smaller than sprocket 193 substantially to the ratio of the diameters of the pulleys 191 and 190. Upon the free end of the shaft 192, a provide a ratchet 196. That 5 ratchet is operatively engaged by the pawl 197. The pawl 197 is eccentrically mounted by means of an adjustable shoulder stud 198 in a slot of the disc 199. That disc is mounted upon the free end of shaft 57 where said shaft extends 10 from the bracket 59. Since the shaft 57 makes one revolution for each operative cycle of the machine, the pawl 197 feeds the belts 198 for a short distance towards the plate 186 during each 15 cycle of the machine. This feeds the books 185, 18 which stand backs-up upon the belts 189 against the plate 186, the belts 189 sliding underneath said books after the books have been stacked tightly against the plate 186.

One book, the book resting against the plate 20 186, is transversely pushed along the plate away from the belts 189 by the jaw 200. The jaw is less thick than one of the books and forms part of a slide 201, which is transversely movable in a slot 202 of plate 186. A link 203 connects the 25 slide 201 to the pitman 204, which is mounted upon a shaft 205. Shaft 205 is supported by a bracket 206 extending from the wheel side of the machine, and carries upon one end the arm 207 with roller 208. The roller 208 is tensioned 30 by a spring 209 against the drum cam 210, which is mounted upon shaft 57.

During each cycle of operations of my machine, the cam 210 causes the jaw 200 to move transversely back and forth in the plate 186, 35 each time feeding one book from the stack of books through a clearance opening in front of one angle 184 onto a trough 211 (Fig. 16). The plate 186, which comprises at its lower end the said trough 211 will ordinarily be long enough to 40 accommodate one book 212 (Fig. 1) between the stack 185, and the inclined plate 187. The jaw 200 moves transversely to just about the width of one book, the book which has been removed from the stack by said jaw during its prior back 45 and forth movement, being pushed transversely towards the gear side by the next book. The trough part 211, which is superimposed upon the lower end of plate 186 extends for a certain distance across the plate 187, which is mounted 50 by means of lateral extensions 214 (Fig. 1) upon lugs 213 (Figs. 2 and 3) extending from the drum stands 37 and 38. Upon the gear side of plate 187 a trough 215, similar to trough 211 and substantially in alignment therewith, arises from 55 plate 187 (Figs. 1 and 16). Between troughs 211 and 215 fits another trough 216 which is mounted upon a slide 217. The slide 217 slides in the plane of plate 187 up and down. In Fig. 1 it is shown to push up, by means of trough 216, a 60 book 218, which has been pushed by book 212 into the longitudinal alignment in which it is shown.

Upon the face of slide 217 is longitudinally adjustably fastened a bracket 219, upon which is hinged the arm 220. The arm 220 is provided at 65 its lower end with a slot 221 which slidably accommodates the shaft 57. A roller 222 laterally extends from the arm 220 and is engaged upon a cam 223 mounted on shaft 57. Therefore the slide 217 moves up and down during each operating cycle of my machine, each time feeding a book onto the drum 43.

If the stands 61 and 62 are moved further back on the machine, or arrange the respective feeding and cutting mechanism horizontally below the 70 75

book feed 35, or make the book feed longitudinally shorter, the book feed may be arranged directly upon the machine, in front of or above the feeding and cutting mechanism, instead of 5 extending therefrom on the hand wheel side. In that case the transverse feed behind plate 186 may be dispensed with, the belt conveyor 189 feeding the books directly onto plate 187 as shown in Fig. 17. In this instance the ratchet shaft 10 192 with pulleys 191 is arranged below the plate 187, and the angles 184 extend backwardly from said plate. A bite 224 takes, in the case of this modification, the place of the trough 216, said bite lifting a book from the front of the stack 15 of books 185 directly up onto the drum. The book 218 is shown in Fig. 3 to be raised in this manner. This operation is timed with the arrival of a flat position 44 on the drum in the position 44A. While the flat position 44A moves 20 in a clockwise direction around shaft 47, the bite 224 correspondingly raises the book, until the book 218 and position 44 arrive below endless belt 226 extending over the idler pulley 225. Since the pulley 225 is substantially radially movable in respect to shaft 47, as will be presently explained, the book may then be gripped between 25 the belt 226 and the blank 117A of position 44A, said blank being held in position by the gripper 154A.

30 From the front and rear stands 37 and 38 forwardly extend arms 227 and 228, upon which is longitudinally adjustably journaled the shaft 229. Shaft 229 carries a gear 230 which is rotated, in cycle with the operations of the machine, by the gear 48. The idler pinion 232, which is mounted upon an arm 231 extending from stand 38, operatively connects the gear 230 with gear 234 on shaft 233. Shaft 233 is radially adjustably journaled in the brackets 235 and 236 and it carries the pulley 237 which drives the belt 226, at a linear speed substantially equal to the circumferential speed of the drum 43 (making allowance for the flat positions 44).

45 A slot 238 in arm 239 slidably accommodates the shaft 233. The arm 239 is hinged upon one arm 240 of angle lever 241, which is rotatably supported in extensions 243 and 244 of stands 37 and 38. The other arm 242 of angle lever 241 50 carries the idler pulley 225. From the arm 239 laterally extends a roller 245, which is engaged upon a cam 246 mounted upon shaft 233. For purposes of illustration the cam 246 is shown in Fig. 3 with a rather steep rise in eccentricity. 55 Of course, it does not have that degree of eccentricity, because it simply serves to rock the angle lever 241 so that the pulley 225 is moved in and out towards the drum in order to engage upon the blank and the book fed under belt 226 and in order to follow the circumference of the drum 43, which is irregular owing to the flat positions 44. A set of idler pulleys 247 and 248 60 are supported by a shaft 249 bridging extensions 243 and 244, and by arms 250, which are supported by shaft 249, respectively, and they take up the slack in the endless belt 226.

While the properly positioned book and blank are retained upon the circumference of the drum 43 by the belt 226, the side folders come into 70 action, fold over the said flaps 120 and 121 of the blank, and finally hold the book on the plate 176 at the flat position 44, (Figs. 3, 10 and 12). Underneath the flat positions of drum 43 lugs 251 extend substantially radially from the circumference of the drum flanges 45 and 46 into

the spaces between adjoining spokes of said flanges (Fig. 18). These lugs are slotted, and in slots the pair of flat bars 252 and 253 are slidably accommodated. These bars are adapted to slide upon each other, being suitably held together by shoulder screws 254 extending through slots in bar 252, and the spring 255 serves to tension the bars away from each other, while they remain in slidable contact, so that the lugs 256 and 257 at the respective ends tend to move away from each other. The bars are also tensioned towards shaft 47. Therefore they engage radially inwardly as well as oppositely transversely outwardly upon the two faces 258 and 260, and the two faces 259 and 261, of the cam sections 262 15 and 263 respectively. These cams are respectively fastened upon the insides of the gear side and hand wheel side drum stands 38 and 37.

From the bars 252 and 253, flat bars 264 and 265 radially extend slidably into slots in lugs 266 20 which are fastened upon shaft 47. The springs 267 extend between the bars 264 and 265 and the lugs 266, thus forcing the lugs 256 and 257 onto the faces 258 and 259 of the cams 262 and 263, respectively.

Upon the flat bars 252 and 253 are transversely adjustably mounted the horses 268 and 269. These horses carry at their upper ends, the angle pieces 270 and 271. Since the books, regardless of their widths, are ordinarily permanently aligned on one side,—in this exemplary execution with the outside of the drum flange 46,—no transverse adjustment on horses 268 is necessary. But to the extent to which the part 177 of plate 176 is adjusted towards and away from the hand wheel side in order to accommodate the width of a book, the horse 269 is adjusted in the same directions.

It will be seen that the cams 262 and 263 outwardly lift the bars 252 and 253, while the book 40 and blank are retained upon the drum by endless belt 226. The angle pieces 270 and 271 thereby turn up the flaps 121 and 120 of the blank. The faces 260 and 261 then press the lugs 256 and 257 at the ends of the flaps towards each other, 45 so that the angle pieces 260 and 261 fold the flaps onto the top of the book. Since in further clockwise direction the cam faces 258 and 259 are receded towards the shaft 47, the angle pieces 270 and 271 come to rest upon the turned over, 50 folded flaps 121 and 120, holding the book on plate 176.

The book being thus retained upon the flat position of the drum, the rear flap is folded over as soon as the book passes away from under belt 55 226 and pulley 237. The folding of the rear flap is brought about by the angle piece 272, which is disposed to substantially the width of the largest book, extending through suitable recesses in the drum flanges (Figs. 3, 13 and 14). Angle 272 60 is mounted upon the ends of arms 273, which are slotted near their rear ends, slidably accommodating a shaft 274, which is rotatably supported in the spokes of the drum flanges 45 and 46. The shaft 274 carries at its gear side end a roller 65 arm 275 with a roller 276. Said roller is tensioned onto a cam 277 which is stationarily mounted upon the inside of the gear side drum stand 38. The shaft 274 also carries a gear 278, which meshes upon a gear 279. The latter is mounted 70 upon a shaft 280, which carries cams 281 in longitudinal alignment with the arms 273. The arms 273 are tensioned against the cams 281, by a spring 283 which is shown in Fig. 14 to extend between the shaft 280 and the angle piece 272. 75

The drum flanges 45 and 46 rotatably support a shaft 284, which carries at its gear side end a roller arm 285 with a roller 286. That roller is tensioned towards a shaft 47 and travels over the cam pieces 287 and 288, which are mounted upon the inside of the gear side drum stand 38. In the modification shown in Fig. 3, the shaft 284 carries arms 289, on which rest rollers 290 are pressed onto said arms by spring tension, said rollers being mounted upon the arms 273. The tension of spring 283 causes the rollers 290 on the arms 273 to be pressed in that instance upon the arms 289. In the modification of Figs. 13 and 15, the curved arms 291, which are mounted upon shaft 284, are hingedly connected to the arms 273 by links 292.

The angle piece 272 is raised from the position in which it is shown in sector A of Fig. 13 to that of sector B by the cam 287. The roller arm 275, actuated by cam 277, rotates the cam 281 which in turn pushes the arm 273 in a clockwise direction around shaft 274 and, thereby, the angle pieces 272 over the book 218. After the roller 286 has rolled off the cam 287, the angle piece 272 comes to rest upon the rear flap, which thus has been folded over the rear of the book.

When the book 218 is placed onto the flat position 44 it will ordinarily align with the rear plate 176. More or less long books will therefore not be in alignment with the front edge of the plate 176, (unless said front plate is longitudinally adjustable as it is adjustable in width). The means folding over the front flap 118 of the blank must therefore be moved along the circumference of the drum according to the length of the book. For that reason the shaft 293 of the front flap folder, shown in Fig. 3, and in the sectors C and D of Fig. 13 is supported by brackets 294, which are circumferentially adjustably mounted upon the outsides of the drum flanges 45 and 46. Shaft 293 extends through suitable slots in the drum flanges.

The front flap folder 295 is mounted upon shaft 293, fitting through a clearance opening 496 in the front flap supporting plate 158 (Fig. 10). The front flap folder 295 is actuated by the roller 286, on roller arm 297. The roller arm 297 is mounted upon the hand wheel side end of shaft 293 and it is operated by the cam 298, which is mounted upon the inside of the hand wheel drum stand 37 and which is indicated in a dot-dashed line in Fig. 13.

The roller arm 297 is normally tensioned in clockwise direction into its position of Sector C of Fig. 13, in which position the front flap folder is disengaged from the book. During further rotation of the drum the roller 296 strikes the nose 299 at the end of the cam 298, and is swung through about 140 degrees into the position of Sector D of Fig. 13, engaging upon the front flap of the blank extending over the front of the book, said front flap having in the meantime been turned onto the book by the device which will be presently explained. When the shaft 293 reaches substantially its lowest position during the rotation of the drum 43, the roller 296 snaps over the end of cam 298 back into the position of Sector C of Fig. 13, thus releasing the book.

The shaft 229, which makes one revolution during the time of one operating cycle of my machine, carries, near the center of the machine, a sector 300 from which a transverse plate 301 extends towards the gear side and, separately, two transverse plates 302 and 303, the convex faces 75 of all of which protrude to the pitch diameter of

gear 230 (Figs. 1 and 3), having therefore the same peripheral speed of rotation in counter clockwise direction as the surface of the front flap supporting plate 150 mounted upon the circumference of the drum 43, and rotating in clockwise direction. The faces of sector 300 and plates 301, 302 and 303 correspond, if developed, to the strips of glue indicated in Fig. 21 (symmetrically speaking). If the sector 300 with the plate 301 is moved towards the gear side of the machine, the developed face of these parts will correspond symmetrically to the gummed strips of Fig. 23.

These gum strips are applied to the front flap of the envelope by the said parts, while they roll over the flap 118 resting on the front flap supporting plate 150 and an adjustment for different widths of envelopes is brought about by moving the sector and plates along the shaft 229. The spaces between the faces of the plates 301, 302 and 303 are provided in order to clear the two gripper fingers 154, the position of which in relation to the front supporting plate is indicated in Fig. 10.

Below the shaft 229 a roller 304 is provided for, which is driven by a gear 305 meshing into the gear 230, and which is partly submersed in the contents of a tank 306 suspended from a bar 307 resting upon the arms 227 and 228 extending from the hand wheel side and gear side drum stands 37 and 38. It applies the paste or gum to the faces 30 of the sectors and plates 300, 301, 302 and 303.

The box 308, in which the shaft 229 is journaled, is fastened upon plates 309 resting on top of the arms 227 and 228, said box being tensioned backwardly against the set screw 310. An eccentric rod 311 extends through the plate 309 and through the extreme upper front ends of arms 227 and 228. By rotation of the handle 312, which is fastened upon the end of rod 311, the shaft 229, may be pulled away from the drum for a short distance, so as to disengage the sectors and plates 300, 301, 302 and 303 from the surface of the front flap supporting blades when the gumming of the flaps is to be temporarily suspended.

Fingers 313 are longitudinally, frontwardly disposed below tank 306, extending from a shaft 314 which is supported in the drum stands. These fingers prevent the throwing-up of the front flap 118 into adhesion with the bottom of the tank 306, when that flap is turned over onto the book after it has been released from the gripper fingers 154.

After the front flap has been released, it is raised in the modification of Figs. 1, 3, 10, and 13, 55 from the supporting plate by the arms 172 extending from the back of the gripper fingers 154, so that it comes to rest on top of the roller 315. That roller is supported between arms 316 mounted upon the shaft 317 (as shown in Fig. 3). The shaft 317 is mounted upon radial extension 319 and 318 of the wheel side and gear side drum stands 37 and 38.

The lever 320, which frontwardly extends from shaft 317, serves to rotate the shaft 317, so that the roller 315 is moved towards and away from the drum 43. From the free end of lever 320 depends an arm 321, which is slotted at its lower end, slidably accommodating a shaft 322 which rotatably extends across the stands 41 and 42. 70 The shaft 322 is operatively-connected with the gear 43 by a train of gears 323, 324 and 325, said shaft rotating in synchronism with the cycles of my machine. The arm 321 is provided with a roller 326 at its lower end, which is actuated by 75

a cam 327 mounted upon the shaft 322. A rocking motion is thus imparted by the cam 327 to the arms 316, which support the roller 315, the motion of said roller being such that it is pressed onto the book position 44, which has proceeded a little further in clockwise direction from the showing of Fig. 18. The front folder 295 (see sector D of Fig. 13) holding the front of the book, roller 315 now rolls over the front flap after it has been turned over onto the book, pressing the gum strips of the front flap (Fig. 21), onto the wheel side flap 120 and rear flap 119 of the envelope blank.

The gum strips 328, 329, 330 and 331, which correspond to the faces of the sector and plates 300, 301, 302 and 303, clear the edges of the front flap 118. The gum strip 328 clears the hand wheel side margin of the flap in order to allow the flap to be depressed by the roller 315 between the side flap folding angles 271 and 278, which overlap the book for a short distance. The angles 271 and 278 may therefore hold the book (like the other folders) until it is released by all folders at once. The gummed strips 329, 330 and 331 are rearwardly arranged from the front edge of the front flap of the blank in order to be depressed into contact with the rear flap 119 by the roller 315, before said roller has travelled to the edge of the front flap 118 so that said roller may be lifted away and will not touch the flap 119 and possibly upset it, and it also will more readily clear the rear folding angle 272 which is still engaged upon the book.

In order to be able readily to adjust the roller 315 to the width of the front flap of the blank used, it is made in two sections, one of which is rotatably and thrustwise supported by the arms 316 on the gear side of the machine; the other one is similarly supported on the arm 316 on the hand wheel side of the machine; but the latter arm 316 is transversely adjustable upon shaft 317, along the keyway 332. The shaft 333 of the wheel side section 334 of the roller 315, slidably extends into the gear side section 335 of said roller. In this manner the length of the roller 315 may readily be adjusted, unless rollers of different lengths are exchangeably used for different widths of envelopes.

The front folding and gripping means, which have been heretofore described, may be replaced by the modified parts indicated in Figs. 18 and 19. A front flap folding angle 336 is here indicated to extend across substantially the full width of the book and front flap supporting plates. The flanges 45 and 46 are recessed at 337 in order to clear said angle. The angle is mounted upon the arms 338, which are supported at their other ends, by means of slots provided therein, upon a shaft 339. Shaft 339 rotatably extends between the flanges 45 and 46. It carries at its gear side end a roller arm 340 with a roller 341. That roller is tensioned onto a substantially circular cam 342, which upon the inside of the gear side drum stand 38 is super-imposed upon the cam 277. The periphery of cam 342 clears at all points of its circumference the cam 277, so that the roller 276 operating on cam 277, and the roller arm 275, always clear the cam 342.

70 A lever 343 extends from shaft 339 and is connected by a link 344 to a lever 345. The lever 345 is fastened upon shaft 346, which carries, substantially in alignment with the arms 338, the cams 347.

75 The book supporting plate 348 is in this in-

stance entirely detached from the front flap supporting plate 349 and is longitudinally as well as transversely adjustable in length and in width as will be explained later. The cam 347 moves the angle 336 in the direction of the plane of plate 348, in order to fold over the front flap 118 of the blank. Since the supporting plate 348 will be adjusted for different lengths of books in that direction, the surface of the cam 347 is spirally disposed, so that it just has to be angularly set upon shaft 346 in order to push the angle 336 for a certain distance over the book on plate 348, to whatever distance said plate extends over the recesses 337 in the drum flanges. The mechanism and movement by which the arm 338 is raised and lowered in the recess 337 is equivalent to the mechanism and movement used in the showing of sectors A and B of Fig. 13 for raising the angle 272. It comprises a roller arm 350 mounted upon the hand wheel side of a shaft 351, which rotatably extends across the flanges 45 and 46, and the levers 352 extending from shaft 351, and connected at their free ends by links 353 to the arms 338. The roller 354 on roller arm 350 is engaged by cam members 355 mounted upon the hand wheel 37 of the drum stand.

In this modification of my machine, I eliminate not only the folder 295, but also the kick-up extension 172 at the back of the gripper fingers 154. The gripper finger 356 is therefore shown without a rear extension in Fig. 18, and the depression 171 on cam 169 may be dispensed with. The angle 335 raises the flap 118 of the envelope blank in this instance, and folds it completely over onto the back with the aid of the air passing thereover, so that the roller 315 serves only to depress the front flap of the blank onto the book, and that the gum strips on the front flap are pressed onto the other flaps with which the front flap is to be sealedly connected. The four folders or folding angles may therefore hold the book upon all four sides, until it is released by them by a reversal of the folding steps, and drops down onto the carriage 357. The angle 336 is provided with clearance openings 358, which clear the stops 359 on carriage 357 (Fig. 20).

The construction of the book supporting plate 348 and of the front flap supporting plate 349 used in connection with the modifications of Figs. 18 and 19 is illustrated in Figs. 22 and 24. The respective plates are shown to be adjusted in Fig. 22 for a larger envelope blank, Fig. 24 shows them for a smaller envelope blank. Figs. 21 and 23 show the respective blanks. In Figs. 22 and 24 the plates are shown to be mounted upon developed sectors of like length of the drum flanges 45 and 46. The book supporting plate 348 is shown to consist of four sections 360 and 361, 362 and 363; the section 360 is fixedly mounted upon the flange 46, whereas the sections 361, 362, and 363 can be adjusted and fastened upon flanges 46 and 45 in the positions indicated in Figs. 22 and 24 as well as in intermediary positions. The plate 360 is shown in Fig. 22 to extend over recess 337. In Fig. 24 it is collapsed so as to coincide at its front edge with one side of said recess. The front flap supporting plate 349 clears the recess 337, in Fig. 22, whereas it is shown to be adjusted in counter clockwise direction upon the flanges 45 and 46 in Fig. 24, so that it extends over the recess 337 and fully supports the flap during the gumming operation.

The carriage 357 is longitudinally travellably

supported by means of wheels in the channel shaped tracks 365 and 364, which are connected by a bottom plate 366 and which are mounted upon a shaft 367. That shaft is rotatably supported upon the printing press stands 369 and 370 upon the hand wheel side and gear side of my machine. When the enclosed book 368 of Fig. 25 is released from the drum, the part facing away from the drum drops onto the carriage 357, and the book is then positioned upside up on the carriage, as seen in Fig. 20. It is retained in position upon the carriage by the book stops 359 mounted upon the carriage 357, by the angle piece 371, which is stationarily mounted upon the carriage on the gear side, and by the angle piece 372 which is transversely adjustably mounted upon the carriage 357 on the hand wheel side of the machine. The rear of the carriage and of the frame supporting the same is raised so as directly to receive the book from the drum 43, when it is released therefrom. The carriage is then lowered, being swung around shaft 367 in counter-clockwise direction by means of the arm 373, which is hinged upon a lug downwardly extending from the plate 366, and the slotted end of which extends over the shaft 322. Arm 373 carries a roller 374, which is engaged upon a cam 375 mounted upon shaft 322.

An ear 376 extends down from the carriage 357 and is connected by the link 377 to the upper end of the two-armed lever 378. The lever 378 is fulcrumed upon a rod 379, which extends between the two stands 41 and 42; its lower, free end is hinged upon the roller arm 380 which slottedly extends over the shaft 322. The roller 381 extending from the side of arm 380 is engaged upon by cam 382, which is mounted upon the shaft 322.

The carriage 357 is in its back position, when it receives the book 368 from the drum. The cam 382 then rolls the carriage forwardly by means of the lever 378, and the arm 373 in the meantime raises the front end of the book and carriage, so that the front end of the book now faces the gap between rollers 383 and 384. The roller 384 is mounted upon the shaft of the intermediary gear 324 and travels at a peripheral speed equal to the linear speed at which the feeding movements of my machine generally take place.

The gear 324 connects by means of the idler gear 385, to a gear 386, on the blank cylinder of the printing press. The gear 386 is connected by a train of gears 387 and 388 to a gear 389 on the shaft 390 of the form cylinder of the printing press. The vertically movable roller 383 is driven by a chain 391 from the shaft 390 of the form cylinder at the same circumferential speed as the roller 384—the roller 392 serving to take up the slack on the chain 391; the rollers 383 and 384 feed the book in between the blanket and form cylinders. The form cylinder 397 is inked by a chain of rollers 393, 394, 395 and 396, from the ink roller 398, which is mounted in the ink tank 399, on a shaft 400, said shaft being driven by a sprocket 401. The sprocket 401 is connected by a chain 402 to the sprocket 403, which is coupled with the gear 404 rotating upon the idler stud 405 on stand 41. Gear 404 is driven from shaft 322 by the pinion 406 protruding from the hand wheel side of the machine.

The shaft 322 is connected by a chain 407 on the gear side of the machine to a sprocket 408 on a shaft 409 extending across the stands 41 and 42. The shaft 409 carries the gear 410, which drives the gear 411 on conveyor shaft 412. The con-

veyor shaft 412 carries a pulley 413, over which extends one end of the endless belt 414. The other end of said belt is supported by a pulley 415. The pulley 415 is mounted between two brackets 416, which frontwardly adjustably extend from a frontward extension 417 arranged upon the two stands 41 and 42. By means of a chute 418, the enveloped books 419 drop onto the conveyor belt 414, after their face sides have been printed by form cylinder 397.

While I have shown and described my invention with some degree of particularity, it will be realized that other modifications and changes may be resorted to under special conditions. I therefore do not wish to be limited and restricted to the exact details shown and described, but reserve the right to make such changes and modifications as may fairly fall within the scope of the subject matter now being claimed.

What I claim is:—

1. Enveloping means for flat objects, comprising a plate supporting said objects positioned on envelope blanks the flaps of which extend beyond the sides of said objects, said supporting plate being expansible length-and crosswise so that the edges thereof may be adjusted to register with the sides of various sizes of said objects, folding devices surrounding said supporting plate below said flaps, and means extending said folding devices over said objects, so that said flaps are folded onto said objects.

2. An enveloping machine for flat objects, comprising means supporting said objects in position on an envelope blank the flaps of which extend beyond the sides of said objects, flap folding devices surrounding said means on all sides and adapted to close in thereabove, and cams stationary relatively to each other but continuously moving in relation to said devices and to said means and actuating said devices.

3. In an enveloping machine for flat objects, in combination with devices building up and closing an envelope around said objects, a carrier drum, segmental flats spacedly provided on said drum each surrounded by said devices and adjustable in length and width to carry said objects, and a mechanism cyclically actuating said devices and moving said drum through the angular distance between said flats.

4. In an enveloping machine for flat objects, in combination with devices building up and closing an envelope around said objects, a carrier drum on which said devices are mounted, flats on said drum each surrounded by a set of said devices and supporting said objects on said drum, cams stationarily mounted on said machine in operative alignment with said devices, and a mechanism continuously rotating said drum, said cams actuating said devices in cycles corresponding to the period of travel of said drum through the angular distance between said flats.

5. In an enveloping machine for flat rectangular objects, in combination with devices folding the flaps of an envelope blank over the four sides of said objects, a carrier drum, segmental flats spacedly provided on said drum and adapted to carry said objects, and a mechanism continuously rotating said drum successively actuating said devices but retaining all devices in folded over holding engagement upon said object until the object is fully enclosed.

6. In a machine for enclosing flat objects in envelope blanks, a frame, a drum mounted on said frame, flat and cylindrically disposed faces alter-

natingly disposed upon the circumference of said drum and adapted respectively to support said objects positioned on said blanks and flaps of said blanks, gumming means with cylindrically disposed faces mounted in said frame and adapted to engage upon and to gum said flaps supported by said cylindrical faces, and a mechanism oppositely rotating said drum and said means at like peripheral speeds of the respective cylindrical faces.

5 7. In a machine for enclosing flat objects in envelope blanks, a frame, a rotating drum mounted in said frame, flat faces on said drum adapted to support said objects positioned on said blanks 15 on top of said faces, folding devices mounted upon said drum, arranged around said flat faces, and adapted to close in from the sides, front and back, successively above said faces and objects, folding said flaps and holding said flaps onto 20 said objects and the latter on the said faces, and means mounted on said frame and engaging upon and actuating said folding devices while said drum rotates.

25 8. In a machine for enclosing flat objects in envelope blanks, a frame, a drum rotatably mounted in said frame, flat faces on said drum adapted to support said objects positioned on said blanks, the flaps of said blanks extending from between said objects and said faces, folding devices mounted upon said drum and arranged around said flat faces, and stationary means mounted on said frame and raising and closing said folding devices above said flat faces while said drum rotates.

30 35 9. In a machine for enclosing flat objects in envelope blanks, a frame, a rotatable drum mounted in said frame, flat faces on said drum adapted to support said objects positioned on said blanks, the flaps of said blanks extending from 40 between said objects and said faces, side folding devices mounted on said drum substantially underneath said flaps and adapted to be raised above said faces and to close said flaps thereabove and temporarily holding said objects on said faces, 45 and means mounted on said frame and actuating said devices.

35 40 10. In a machine for enclosing flat objects in envelope blanks, a frame, a rotatable drum mounted in said frame, flat faces on said drum adapted to support said objects positioned on said blanks, the flaps of said blanks extending from between said objects and said faces, flap folding devices mounted on said drum substantially underneath said flat faces and adapted to be raised above said faces and to close in thereabove, 45 an endless belt travellably mounted upon said frame and adapted to engage upon part of the circumference of said drum, and means mounted on said frame and actuating said devices, said belt and said devices successively holding said objects onto said faces.

45 50 11. In a machine for enclosing flat objects in envelope blanks, a frame, a rotatable drum mounted in said frame, flat faces on said drum adapted to support said objects positioned on said blanks, the flaps of said blanks extending from between said objects and said faces, rollers mounted in said frame, one of said rollers being movable towards and away from said drum, 55 and an endless belt extending over said rollers and adapted to engage upon part of the circumference of said drum and to retain said objects on said drum.

50 55 12. In a machine for enclosing flat objects in envelope blanks, a frame, a rotatable drum

60 mounted in said frame, flat faces on said drum adapted to support said objects positioned on said blanks, the flaps of said blanks extending from between said objects and said faces, rollers mounted in said frame, one of said rollers being 65 movable towards and away from said drum, an endless belt extending over said rollers and adapted to engage upon part of the circumference of said drum and to press said objects onto said drum, and means raising said movable roller 10 from said drum.

65 70 13. In a machine for enclosing flat objects in envelope blanks, a frame, a rotatable drum mounted in said frame, faces on said drum adapted to support said objects positioned on said blanks, the flaps of said blanks extending from between said objects and said faces, a pair of rollers mounted in said frame, one of said rollers being movable towards and away from said drum and onto said faces, the other roller being adjustable towards the largest periphery of said drum, and an endless belt extending over said rollers and adapted to engage upon part of the circumference of said drum and to retain said objects on said drum.

75 80 14. In a machine for enclosing flat objects in envelope blanks, a frame, a drum mounted in said frame, flat and cylindrically disposed faces alternatingly disposed upon the circumference of said drum and adapted respectively to support said objects positioned on said blanks and flaps of said blanks, a flap folder mounted upon said drum substantially between said flat and cylindrically disposed faces, means raising said folder above said faces, whereby said flap is lifted from said cylindrical face, and means shifting said raised folder onto said objects folding said flap thereonto, and holding said objects on said faces when they are swung into an upside-down position underneath said drum during rotation of said drum.

85 90 15. In a machine for enclosing flat objects in envelope blanks, a frame, a drum mounted in said frame, flat and cylindrically disposed faces alternatingly disposed upon the circumference of said drum and adapted respectively to support said objects positioned on said blanks and flaps of said blanks, a flap folder mounted between said flat and cylindrically disposed faces, means raising said folder, shifting said raised folder onto said object and folding said flap thereonto, a 95 roller mounted on said frame and adapted to be moved onto said drum, and means pressing said roller onto said flap folded onto said object.

95 100 16. In a machine for enclosing flat objects in envelope blanks, a frame, a drum mounted in said frame, flat and cylindrically disposed faces alternatingly disposed upon the circumference of said drum and adapted respectively to support said objects positioned on said blanks and flaps of said blanks, a roller mounted on said frame and adapted to be moved onto said drum, means lifting said flaps from said cylindrical faces onto said roller, and means pressing said roller onto said flaps.

105 110 17. In combination with the rotating carrier drum of an enveloping machine, means feeding envelope blanks onto the circumference of said drum, means spreadedly retaining said blanks on said drum, means superimposing the objects to be enveloped upon said blanks spread upon said drum, means first engaging said objects upon said drum in registry with said blanks, and folding means bending over said blanks onto said objects while they are being engaged by said first en-

gaging means and engaging said objects upon said drum after said objects have been released from said first engaging means.

18. In a device of the character described, a carrier continuously moving through like cycles of operations, a mechanism feeding envelope blanks onto said moving carrier, a mechanism feeding objects onto said blanks on said moving carrier, means temporarily retaining said blanks and said objects on said carrier as fed thereonto, devices folding a pair of opposite flaps of said blanks onto said objects and temporarily holding said blanks and said objects on said carrier after they have been released by said means, and devices folding over the remaining flaps while said blanks and objects are thus being held on said carrier.

19. In a device of the character described, a carrier continuously moving through like cycles of operations, a mechanism feeding envelope blanks onto said moving carrier, a mechanism feeding objects onto said blanks on said moving carrier, means temporarily retaining said blanks and said objects on said carrier as fed thereonto, a mechanism gumming said blanks on said moving carrier, and devices folding opposite flaps of said blanks onto said objects and temporarily holding said blanks and said objects on said carrier after they have been released by said means, while said blanks are being gummed.

20. In a device of the character described, a rotating drum carrier continuously moving through like cycles of operations, a mechanism feeding envelope blanks onto said moving carrier, a mechanism feeding objects onto said blanks on said moving carrier, a mechanism feeding objects onto said blanks on said moving carrier, means temporarily retaining said blanks and said objects on said carrier as fed thereonto, and devices transversely folding flaps of said blanks onto said objects and retaining said blanks and said objects on said carrier after they have been released by said means.

21. In a device of the character described, a carrier continuously moving through like cycles of operations, a mechanism actuated in cycle with said carrier and cutting envelope blanks from a web, a mechanism feeding said envelope blanks onto said moving carrier, a mechanism feeding objects onto said blanks on said moving carrier, means temporarily substantially centrally engaging upon and retaining said blanks and said objects on said carrier as fed thereonto, and devices folding the side flaps of said blanks onto said objects while said blanks and objects are thus engagedly retained and temporarily retaining said blanks and said objects on said carrier for successive operations after they had been released by said means.

22. In a device of the character described, a carrier continuously moving through like cycles of operations, a mechanism feeding envelope blanks onto said moving carrier, a stationary stand holding objects substantially tangentially to said carrier, and a mechanism removing objects from said stand and feeding them onto said blanks on said carrier substantially at the speed of surface movement thereof.

23. Enveloping means for a flat object, comprising a support with edges substantially registering with the sides of said object and adapted to support said object in position on an envelope blank the flaps of which extend beyond the sides of said object, folders for said flaps surrounding said support below the top of said support, and a plurality of folder actuating means operatively engageable with extending said fold-

ers over said object when said means are moved relatively to and substantially parallel to the surface of said support so that said flaps are folded onto said object.

24. In a machine comprising means cyclically enveloping objects of various sizes in correspondingly longer or shorter envelope blanks, cylinders rotating and transversely cutting envelope blanks in cycle with said means and of a circumference exceeding the length of the longest blanks to be made, means continuously feeding into said cylinders paper for envelope blanks, means operatively, and adjustably in respect to feeding speed, connecting said feeding means with said cylinders, and a covering on one of said cylinders brushingly engaging said paper between cutting operations.

25. In a machine comprising means cyclically enveloping objects of various sizes in correspondingly larger and smaller envelope blanks, cylinders rotating in cycle with said means, angular cutting elements peripherally disposed on said cylinders and each adapted to cut one of the corners between adjoining flaps of the largest envelope blanks to be made, and means for peripherally and transversely adjusting in respect to each other said elements on said cylinders.

26. In a machine comprising means cyclically enveloping objects of various sizes in correspondingly larger and smaller envelope blanks, cylinders rotating in cycle with said means, angular cutting elements peripherally disposed on said cylinders and each adapted to cut one of the corners between adjoining flaps of the largest envelope blanks to be made, and peripherally aligned in two pairs as well as transversely aligned in two pairs on said cylinders, and means peripherally adjusting said transversely aligned pairs in respect to each other and transversely adjusting said peripherally aligned pairs in respect to each other.

27. In a machine enveloping objects in blanks, a rotating drum, a mechanism feeding one of said blanks and engaging it on said drum, a plate substantially tangentially directed onto said drum in the direction of the rotation thereof and supporting one of said objects resting thereon, means sliding said one object off said plate onto said drum, and means engaging the end of said object on said drum on top of said one blank, as it is slid thereonto.

28. In a machine enveloping objects in blanks, a rotating drum, a mechanism feeding one of said blanks and engaging it on said drum, a plate substantially tangentially directed onto said drum in the direction of the rotation thereof, means placing one of said objects onto said plate, means sliding said one object off said plate onto said drum, and means engaging the end of said object on said drum on top of said one blank, as it is slid thereonto.

29. In a machine enveloping objects in blanks, a rotating drum, a mechanism feeding one of said blanks and engaging it on said drum, a plate substantially tangentially directed onto said drum in the direction of the rotation thereof, means moving angularly towards said plate, supporting said objects and pressing them onto said plate, means sliding one object off said plate onto said drum, and means engaging the end of said object on said drum on top of said one blank, as it is slid thereonto.

30. In a machine enveloping objects in blanks, a rotating drum, means on said drum enveloping said objects in said blanks, a mechanism longi-

tudinally aligned with said drum and feeding said blanks onto said drum, a means transversely offset from said drum and said mechanism and holding said objects, a mechanism transversely 5 moving one of said objects into longitudinal alignment with said drum, and means engaging said one object on said drum on top of one of said blanks.

31. In a machine enveloping objects in blanks, 10 a carrier, means supporting a stack of said objects, a plate arising from said means, one of said objects resting against said plate, a trough aligned with said means and plate and forming a transverse continuation thereof, a mechanism 15 transversely moving one of said objects from said means onto said trough, and means lifting said object out of said trough onto said carrier.

32. In a machine enveloping an object in a blank which consists of a backing and side and 20 end flaps extending therefrom, a rotating drum, a flap on said drum accommodating said backing, means holding the object to be enveloped on said flap on top of said backing, means folding said side flaps onto said object while it is 25 thus being held, a cylindrical part on said drum, connecting with said flap and accommodating one of said end flaps extending from the backing accommodated on said flap, and means gumming 30 said one flap accommodated on said cylindrical part.

33. In a machine enveloping an object in a blank which consists of a backing and side and 35 end flaps extending therefrom, a frame, a carrier moving in said frame, a plate on said carrier accommodating said backing and supporting the object to be enveloped on top of said backing, flap folders mounted on said carrier on opposite sides thereof, and cams mounted on said frame and closing said folders over said object when 40 they engage on said folders during the movement of said carrier.

34. In a machine enveloping an object in a blank which consists of a backing and side and 45 end flaps extending therefrom, a frame, a carrier moving in said frame, a plate on said carrier accommodating said backing and supporting the object to be enveloped on top of said backing,

stationary cams on said frame, and flap folders mounted on said carrier on opposite sides thereof and raised and moved towards each other by said cams, so that said side flaps are bent over the sides of said object thereonto. 5

35. In a machine enveloping an object in a blank which consists of a backing and side and end flaps extending therefrom, a frame, a carrier moving in said frame, a plate on said carrier accommodating said backing and supporting the 10 object to be enveloped on top of said backing, stationary cams on said frame, and flap folders mounted on said carrier on opposite sides thereof and raised by one and moved towards each other by another one of said cams, so that said side 15 flaps are bent over the sides of said object thereonto.

36. In a machine enveloping an object in a blank which consists of a backing and side and end flaps extending therefrom, a frame, a carrier moving in said frame, a plate on said carrier accommodating said backing and supporting the object to be enveloped on top of said backing, flap folders mounted on opposite sides of said carrier, and means actuating said flap folders, 25 so that said flap folders bend said side flaps over the sides of said object onto the top thereof and engage said object on said carrier. 20

37. In a machine enveloping an object in a blank which consists of a backing and side and 30 end flaps extending therefrom, a frame, a carrier moving in said frame, a plate on said carrier accommodating said backing and supporting the object to be enveloped on top of said backing, stationary cams on said frame, flap folders 35 mounted on said carrier on opposite sides thereof and raised and moved towards each other by said cams, so that said side flaps are bent over the sides of said object thereonto, and means tensioning said flap folders against the action of 40 said first cam, said first cam being shaped to release said folders ahead of the said other cam, so that said tensioning means temporarily press said side folders onto said object and retain said object on said carrier. 45

MATTHEW VIERENGEL
